Marshall & Hawley.
ATTORNEYS

UNITED STATES PATENT OFFICE.

HENRY N. SLEDGE, OF JERSEY CITY, NEW JERSEY.

LOCK MECHANISM.

Application filed January 24, 1925. Serial No. 4,436.

To all whom it may concern:

Be it known that I, HENRY N. SLEDGE, a citizen of the United States, and a resident of Jersey City, county of Hudson, and State of New Jersey, United States of America, have invented certain new and useful Improvements in Lock Mechanisms, of which the following is a specification.

This invention relates to locks.

10 At the present time when holdups are prevalent, bandits will enter a store and compel the clerk or cashier to operate the combination of a safe lock and open the safe. In such holdups, speed is essential since the bandits obviously want to make a quick getaway.

15 This invention has for its salient object to provide a lock so constructed and arranged that a considerable period of time must elapse after the combination of a lock has been worked before the lock bolts can be withdrawn and the safe door or other door can be opened.

20 Another object of the invention is to provide a lock so constructed and arranged that the manual operation of a combination lock or equivalent mechanism will set in operation slow moving power driven means for withdrawing a locking bar or detent thereby permitting the release of the locking bolt after a period of time has elapsed.

25 Another object of the invention is to provide lock mechanism combining a manually operable device with slow moving power driven means for controlling and withdrawing a locking bar or detent.

30 Another object of the invention is to provide lock mechanism combining a manually operable device and power driven mechanism within the control of the operator but set in operation by the manually operated device, said power driven means completing the release of the locking bolt.

35 Further objects of the invention will appear from the following specification taken in connection with the drawings, which form a part of this application, and in which—

40 Fig. 1 is an elevational view of a mechanism constructed in accordance with the invention.

45 Fig. 2 is an elevational view broken away showing the detent withdrawn thereby permitting the operation of the locking bolts.

50 Fig. 3 is an enlarged sectional elevation taken substantially on line 3—3 of Fig. 1, and

Fig. 4 is an enlarged sectional elevation taken substantially on line 4—4 of Fig. 1.

55 The invention briefly described consists of a door locking mechanism which may be of any desired character and includes a detent for retaining the locking bolts against release until the operator has worked the combination or otherwise manipulated the lock to release the detent. In this invention, the 60 detent comprises two sections, one of which is withdrawn by the usual combination lock mechanism. The other section of the detent is adapted to be moved by a power driven means and the withdrawal of the manually 65 controlled section of the detent operates to connect the other section to the power driven means. Any suitable form of power driven means may be used but it is important that this means withdraw the detent section slowly and gradually so that a considerable period of time must elapse before the 70 tent section is withdrawn and releases the locking bolts. Optional means is also provided whereby the manually operated device 75 can be used to release both sections of the tent from the locking bolt. Further details of the invention will appear from the following description.

80 In the particular form of the invention illustrated, the door locking means comprises a disk 10 mounted on a spindle 11 and having pivotally connected thereto, on opposite sides of the spindle, locking bolts 12 and 13. It will be understood that the spindle 11 extends through the door and has a suitable handle secured thereto for rotating the spindle and disk. The disk 10 has an arm 15 extending outwardly from its periphery.

85 The lock control mechanism comprises a detent having a pair of sections A and B. These sections are slidably mounted between rollers 16 and 17 and stops 18 and 19 are provided for limiting the movement of the 90 sections. The section B as shown in Fig. 1 is positioned in the path of the arm 15 and prevents the rotation of the disk 10 unless this section is withdrawn to the position 95 shown in Fig. 2.

100 The section A of the detent mechanism has pivotally connected thereto an arm 20 having an offset end 21 formed thereon. The end 21 of the arm 20 is adapted to enter peripheral notches 22 in a series of tumblers 23 (one of which is shown) when the proper combination has been worked and the 105

notches in the various tumblers are disposed in alignment with each other. When the end 21 of the arm 20 drops into the notches, the tumbler disks can be rotated to the position shown in dotted lines in Fig. 1, thereby moving the section A of the detent to the left against the stop 18.

The detent section B has mounted therein a spindle 30. A lever 31 is secured to one end of the spindle and one end 32 of the lever normally rests on the upper edge 33 of the detent section A. Section A has one end of its upper edge cut away as shown at 34 and when the section A is withdrawn to the left, the end 32 of the lever 31 will drop into the recess 34 and rest on the surface 35 at the bottom of the recess. The lever 31 is extended on the opposite side of the shaft 30 from the end 32 and is further extended upwardly to form an arm 36. An arm 37 is secured to the opposite end of the spindle 30 and is disposed parallel with the arm 36. These two arms are connected by a cross pin or cross rod 38.

25 A power driven toothed wheel or gear 40 is mounted above the detent sections A and B and the teeth of this wheel are so positioned relative to the cross pin 38 that the cross pin will be positioned between the teeth when the lever moves in an anti-clockwise direction and this movement takes place as the detent section A is withdrawn from the left.

It is contemplated that the power driven wheel 40 will be rotated continuously and at a slow rate of speed. After the detent A has been withdrawn and the lever swings in an anti-clockwise direction, the engagement of the cross pin 38 between the teeth of the wheel 40 will cause the detent section B to be gradually withdrawn by power derived from the wheel 40 until it reaches the position shown in Fig. 2 when the lever 31 will be swung in a clockwise direction causing the cross pin to be released from engagement by the teeth of the wheel. When the detent sections have been withdrawn from the position shown in Fig. 1 to the position shown in Fig. 2, the arm 15 of the disk 10 is released and the disk can be rotated thereby withdrawing the locking bolts 12 and 13 from their locking position.

In order to prevent friction between the arm 15 and the detent section B a roller 41 is preferably mounted at the upper edge of the section B in a position to engage the outer end of the arm 15.

It may be desirable at times to provide for the release of the detent sections A, B by the operation of the combination lock without waiting for the power driven wheel 40 to release the detent B. For this reason a latch 50 (see Figs. 1 and 2) is pivoted at 51 to the section A and is adapted to be swung in a clockwise direction to the position shown

in dotted lines in Fig. 2 into engagement with a pin 52 carried by the section B. When the latch is swung to this position, the withdrawal of the detent A will also cause the withdrawal of the detent B. It should be understood that the latch 50 can be operated only from the inside of the door, thus making it impossible for the person endeavoring to open the door to couple the detent sections from outside the door.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. Lock mechanism comprising locking elements, a detent for preventing the operation of said elements, power driven means for withdrawing said detent and manually operable means for setting said means in operation.

2. Lock mechanism comprising locking elements, a detent for preventing the operation of said elements, slow operating, power driven means for withdrawing said detent, means for operatively connecting said power driven means to said detent, means for holding said connecting means in inoperative position and manually operable means for releasing said holding means.

3. Lock mechanism comprising locking bolts, detent mechanism for preventing the movement of said bolts to unlocking position, said detent mechanism comprising a plurality of separately movable elements, manually operable means for moving one of said elements and power driven slow operating means for moving another of said elements.

4. Lock mechanism comprising locking bolts, detent mechanism for preventing the movement of said bolts to unlocking position, said detent mechanism comprising a plurality of separately movable elements, manually operable means for moving one of said elements and power driven slow operating means for moving another of said elements, said last named means being set in operation by the movement of said manually operable means.

5. Lock mechanism comprising locking bolts, detent mechanism for preventing the release of said bolts and including a plurality of elements, manually operable means for retracting one of said detent elements, a continuously operating power driven device and means controlled by said manually retractable element for coupling another detent element to said device.

6. In lock mechanism, a detent comprising

ing a pair of sections, manually operable means for retracting one section, a power driven device, and means controlled by said manually retracted section for connecting said other section to said device.

7. In lock mechanism, locking elements, a detent associated with said elements, a power driven device and manually operable means for effecting the connection of said detent to said device.

8. Lock mechanism comprising locking elements, a detent associated with said elements, a power driven element, means for connecting said detent to said power-driven element and manually operable control means for said connecting means.

9. Lock mechanism comprising a continuously rotating member, a detent, means for connecting said detent to said rotating mem-

ber and manually operable control means 20 for said connecting means.

10. Lock mechanism comprising a power driven rotating member, a detent, means for connecting said detent to said rotating member and manually operable control means for 25 said connecting means.

11. Lock mechanism comprising locking bolts, operating means therefor, detent mechanism for preventing the operation of 30 said operating means, operating means for withdrawing said detent mechanism, and slow operating power driven means connected to one of said operating means, the other operating means being adapted for manual operation.

In witness whereof, I have hereunto set my hand this 21st day of January, 1925.

HENRY N. SLEDGE.
